ATTORNEY

UNITED STATES PATENT OFFICE.

KARL L. HERRMANN, OF DETROIT, MICHIGAN, ASSIGNEE TO THE STUDEBAKER CORPORATION, OF SOUTH BEND, INDIANA, A CORPORATION OF NEW JERSEY.

INTERNAL-COMBUSTION ENGINE.

Application filed August 31, 1925. Serial No. 53,655.

This invention relates to the lubrication of internal combustion engines and more particularly to the splash pans therefor.

In those internal combustion engines employing pressure lubrication the oil is circulated by means of a pump which draws it up through a pipe out of a reservoir and forces it through distributing pipes to the bearings and various other working parts. After being used in these parts, the oil then falls or drips down to the splash pan and is directed into a strainer through an opening in the splash pan where the sediment is removed and then flows into the reservoir where it is again picked up by the pump and distributed.

Considerable dirt and grit are drawn into the crankcase through the breather tube and also some sediment, such as steel dust and the like from the friction surfaces, is picked up by the oil as it is circulated. Much of this sediment is too small to be removed by the strainer screen and continually flows around with the oil to the bearings where it increases wear. Some of it even works its way up between the cylinder walls and pistons increasing the liability of scratched and scored cylinder walls. Sometimes this sediment collects in the distributing pipes which eventually clogs them up and prevents oil from flowing to the working parts causing burned-out bearings and the like.

Many people owning cars are very lax in changing the oil in the crankcase and in many cases do not change it for months at a time. It is especially in these cars that the sediment just mentioned accumulates and does serious damage to the working parts of the engine, and it is to safeguard these people as well as to prevent wear to the ordinary engine that the present invention has been provided.

With the above in view, it is the primary object of the present invention to provide a new and novel means for collecting the sediment from the oil used in an internal combustion engine.

Another object is to provide a splash pan for an internal combustion engine with means for collecting fine sediment from the lubricating oil, which means is simple in construction, easy to assemble and is economical to manufacture.

A further object is to provide an oil splash

pan for an internal combustion engine with a layer of felt or similar material over the entire surface thereof, to remove fine sediment from the lubricating oil as it flows over and through the same.

These being among the objects of the present invention the same consists of certain features of construction and combinations of parts to be hereinafter described with reference to the accompanying drawing, and then claimed, having the above and other objects in view.

In the accompanying drawing which illustrates a suitable embodiment of the present invention and in which like numerals refer to like parts:—

Figure 1 is a partial transverse sectional view of an internal combustion engine having an oil pan and a splash pan embodying the construction of the present invention.

Figure 2 is a broken perspective view of the splash pan shown in Figure 1 illustrating the device of the present invention assembled thereon.

The oil in making its circuit is drawn from the reservoir 10 formed by the walls of the oil pan 11, through a pipe 12 and is forced by a pump or some such device (not shown) through distributing lines to the bearings 13 for the crankshaft 14, the bearings 15 for the connecting rods 16, and to the bearings 17 for the cam shaft 18. Here it falls down to the splash pan 19 and flows toward and through an aperture 20 into a strainer 21, where the heavier sediment particles are trapped and precipitated down into the removable sediment pocket 22. The oil then passes out into the reservoir 10 carrying with it the finer sediment particles which are too small to be removed by the strainer 21 and flow with the oil to the bearings 13, 15 and 17 and other working parts.

To trap these fine sediment particles and also some of the larger ones before they reach the strainer 21, the splash pan 19 is provided with a covering 24 on its entire surface with the exception of the aperture 20 and opening 23 through which the pipe 12 extends, or felt or similar material having a texture of loosely associated fibers. Now as the oil flows from the bearings 13, 15 and 17, on to the splash pan 19 and flow toward the aperture 20, it will tend to seep through the covering 24 and leave the sediment

particles caught in the fibers or filaments of the felt. Small apertures such as 25 may be provided in the bottom of the splash pan to cause the oil to seep through the felt covering 24 faster and to drain into the reservoir 20. Although the openings 25 are preferable, the bottom of the splash pan 19 may be formed with a plurality of corrugations leading to the aperture 20.

10 The covering 24 is preferably held in position in the splash pan 19 by a plurality of split rivets 26 which can be removed when the engine is torn down for repairs, so that the covering 24 can be taken out and a new, clean one inserted in its place.

15 From the foregoing description it can be seen that in employing the use of a felt covering for an engine splash pan fine sediment particles and many larger particles will be caught therein and be prevented from circulating with the lubricating oil into the many working parts of the engine, thereby preventing the same from increasing wear and from clogging the various pipe lines.

20 25 It can also be seen that such a device is easy to assemble and would be very economical to manufacture and use.

Formal changes may be made in the specific embodiment of the invention described 30 without departing from the spirit and substance of the broad invention, the scope of which is commensurate with the appended claims.

What I claim is:—

1. The combination with an internal combustion engine having a splash pan beneath the crank case over which the oil from the bearings passes on its way to the oil reservoir, of felt-like material positioned on said splash pan for intercepting said oil and retaining foreign particles being carried along therewith. 35

2. In a lubricating system for an internal combustion engine, an oil splash pan covered with a relatively thick layer of loosely associated fibrous material to collect foreign particles in said oil. 40

3. In an internal combustion engine lubricating system having an oil pan and a partition dividing said oil pan into an oil reservoir portion and a crankcase portion, a layer of fibrous material positioned on the upper surface of said partition to intercept the oil flowing from said partition into said reservoir to collect foreign particles in said oil. 50

4. In an internal combustion engine lubricating system having an oil reservoir, a cover therefor having a bottom wall and side and end walls, and a layer of fibrous material covering said bottom wall and extending upwardly along said side and end walls to collect foreign particles in the oil flowing over said cover. 55

Signed by me at Detroit, Michigan,
U. S. A., this 21st day of August, 1925.

KARL L. HERRMANN.
